Inventor,

Allan E. Francis.
by Geo. W. Tibbitts, Attorney.

UNITED STATES PATENT OFFICE.

ALLAN E. FRANCIS, OF CLEVELAND, OHIO.

GRAVER-HOLDER FOR ENGRAVING-MACHINES.

SPECIFICATION forming part of Letters Patent No. 435,416, dated September 2, 1890.

Application filed January 24, 1890. Serial No. 338,032. (No model.)

To all whom it may concern:

Be it known that I, ALLAN E. FRANCIS, a citizen of the United States, residing at Cleveland, in the county of Cuyahoga and State of Ohio, have invented a certain new and useful Graver-Holder, of which the following is a specification.

This invention relates to an adjustable holder for securing gravers to the graver-stock of engraving-machines; and it consists of the novel constructions and combination, as hereinafter fully described, and pointed out in the claim.

In the accompanying drawings, Figure 1 represents my new tool-holder having short tool-grip, and Fig. 2 shows the same with a long tool-grip.

A is a ring designed for attaching the holder to the lower end of the graver-stock of the engraving-machine. It is split on one side and has lugs or ears *a a*, through which a clamping-screw is placed. The ring A has an arm connecting it with a second ring A² like the first.

B is a tool-holder having a pin *b*, by which it is attached to said ring A², and has a plate *b²*, with tool-socket C depending therefrom.

In the flanges *b³* on the plate are placed set-screws *c c*, bearing against lugs *c²* on the ring A, by means of which the tool-holder may be accurately adjusted for centering the tool-point.

The tool-socket C, in Fig. 1, is split on one side, and has ears or lugs with a clamping-screw. To the rear side of plate *b²* is provided a diagonal lug *b⁴*, having a set-screw designed for accurately setting the graver lengthwise in its socket. In Fig. 2 the set-screws are a little differently arranged for same purpose.

The object of this tool-holder, as will be readily seen, is to greatly facilitate accurate adjustment of the graver for nice work.

Having described my invention, I claim—

The graver-holder comprising split rings A and A², having the clamping-screws, tool-holder B, having pin *b* adjustably held by ring A², and provided with plate *b²*, flange *b³*, adjusting-screws C C, and tool-socket C, with set-screw *b⁴*, constructed substantially as described, and for the purpose specified.

ALLAN E. FRANCIS.
